ARC PREVENTING SWITCH

Alphonse P. Gauvreau, Cleveland Heights, Ohio,
assignor to Clark Controller Company, Cleve-
land, Ohio, a corporation of Ohio

Application August 20, 1949, Serial No. 111,528

5 Claims. (Cl. 200—146)

1

This invention relates to electric switches or circuit breakers and more particularly to what are known as arc preventing switches.

Opening of a circuit carrying heavy current, especially when that current is utilized in some circuit component to create an electro-magnetic field, causes the opening contacts to become electrodes between which is produced an arc by means of which the stored energy of the magnetic field is dissipated. Since collapse of the magnetic field generates high voltages across the contacts, it tends to continue current flow across the gap and to maintain the arc. When the circuit is opened suddenly and completely, enormous electrical surge pressure is developed, requiring the use of cumbersome and expensive expedients to prevent rupture in system components and safeguard against danger to personnel. Further, in certain situations, such as in aviation, considerations of weight prohibit the use of such expedients.

The present invention aims to satisfy the foregoing and other conditions by associating with the openable main switch contacts a shunt path capable of carrying substantially full load without danger, but which path includes a variable resistance together with means for retarding variation of that resistance over a period (measured, of course, in small fractions of a second) sufficient to enable the magnetic field to slowly dissipate its surge energy without danger either to circuits, apparatus or personnel.

Another object of the invention is to provide improved means, operating in conjunction with switch contacts, for temporarily shunting current flow before closure and after opening of said contacts, and while the shunt is in operation for progressively and slowly varying the resistance therein, thus to gradually dissipate the energy and prevent damage.

Another object is to provide an improved switch mechanism including openable contacts and in shunt therewith a carbon stack or pile, together with means for gradually varying the pressure upon the pile, and thus its resistance, during switch opening and closing movements.

Still another object is to provide improved switch mechanism of the character described in the next preceding paragraph, including means for retarding or slowing variation in the shunt pile resistance during a period sufficient to enable the stored energy of the circuit to gradually dissipate itself without dangerous arcing, upon switch opening.

Further objects of the invention in part are obvious and in part will appear more in detail hereinafter.

In the drawings, Fig. 1 represents a plan view of one form of mechanism embodying the invention;

Fig. 2 is a sectional elevation on the line 2—2, Fig. 1;

2

Fig. 3 is a sectional elevation on the line 3—3, Fig. 1; and

Fig. 4 is a detail sectional view, on the same plane as Fig. 3, showing another form of retarding means.

Referring to Figs. 1 to 3 inclusive, the switch mechanism shown includes an insulating base 10 on which are rigidly mounted two terminal plates 11, 12 to which the lead wires are connected. These terminals cooperate with a vertically reciprocable circuit controlling bridge or contact member 13 normally biased to switch-open position by a spring 14 and advanced to switch-closed position by depression of a pivoted armature lever 15 turning upon a small shaft 16 secured to the base.

To the terminal plates 11, 12 are rigidly secured, as by doweling, two insulated porcelain posts 17, the upper ends of which are similarly secured to an insulated support bar 18, the latter also being secured, by connecting plate 19, to two yokes 20, 21 fastened to the base. Each yoke consists of two strap members cross-connected by a cylindrical rod 22, made of magnetic material and serving as the core of a coil 23. As shown in Fig. 3, each rod 22 and the two yoke straps connected to it form the body of an electromagnet, the two poles of which cooperate with the magnetic lever armature 15, so that upon energization and deenergization of the coil the armature is attracted to and released from gap-closing relation with the magnet poles, as is usual.

A spring 24 biases the armature lever to its retracted position shown in Fig. 3.

The movable end of armature lever 15 lies above an insulated member 25 held to the bridge 13 by a pin 26 to which one end of spring 14 is attached. Above the lever, spring 14 is surrounded by an insulating sleeve 27.

Above the sleeve 27, and strung upon the rods 17 and guided by them, is a load-discharge current-conducting contact bar 28, end portions of which are adapted to be moved into and out of current-conducting contact relation with the upper one of a series of carbon plates 29 of washer form strung upon the pillars 17 below a shoulder 17a on said rods which prevents substantial separation between any two of the carbon plates. In the contact bar 28 is threaded a screw 30 to which the upper end of spring 14 is connected.

Assuming the parts in the switch-open position shown in Figs. 2 and 3, when the coils 23 are energized the armature lever 15 moves down, turning counterclockwise in Fig. 3, its movable end depressing bridge 13 and also, through spring 14, moving downwardly the discharge plate 28.

Before bridge member 13 closes the gap between terminal plates 11, 12, the discharge plate 28 engages the upper ones of the carbon discs of the two piles. These discs lie loosely in contact

with each other and are made of high resistance material. Consequently, at the moment of contact of plate 28 with the piles, the resistance through them is high.

Armature lever 15 continues its downward movement, accomplished by extension of the spring 14 and the gradual application of increasing pressure to the two piles of carbon discs. The effect is to slowly or gradually decrease the resistance through said piles until finally, just before bridge 13 reaches the terminal plates 11, 12, the resistance through the carbon piles has been reduced to such an amount that the circuit through said piles, by way of discharge plate 28, is capable of carrying the current of full load without appreciable voltage drop. This has been accomplished without the production of any arc, or at least any destructive or dangerous arc. Now, as the downward motion of armature lever 15 continues, the bridge 13 engages both of the terminal plates 11, 12, and metallically closes the circuit between them, said terminal plates and bridge 13 carrying the load.

The switch will remain closed so long as the coils 23 remain energized.

Upon deenergization of the coils, the switch opens, by operations as follows:

First, as the armature lever 15 rises, bridge 13 moves out of contact with the terminal plates 11, 12. But no arc is produced, because the carbon discs of the two piles are under pressure and the discharge plate 28 across the two piles, in a shunt circuit around bridge 13, carries the current of the full load traversing said piles. As the armature lever continues its upward movement, the pressure upon the two carbon piles is gradually reduced, with increase in resistance, until finally the circuit is completely broken when the discharge plate moves out of contact with the upper members of the piles.

To avoid the production of any arc, upon breaking the circuit and particularly of any destructive or dangerous arc, the present switch mechanism is provided with suitable means for retarding or slowing up the variation in resistance produced by relieving the pressure upon the two piles of carbon discs. Snap action, or any sudden action comparable to it, would require dissipation of the energy of the magnetic field at the contacts in such a short time as to produce high potential accompanied by arcing effect.

The retarding or restraining means may be of any kind suitable for the purpose.

In Fig. 3, I show the pivoted end of armature lever 15 provided with a semicylindrical friction drum member 31 cooperating with a flexible brake strap 32, one end of which is attached to the base, as at 33, and the opposite end of which is attached to a brake lever 34 mounted therein to turn about the same shaft 16 on which the armature lever is pivoted. Brake lever 34 is made of magnetic material and is in the form of a lever arm working up and down in a slot extending centrally along the armature lever 15. Brake lever 34 is biased upwardly by a spring 35.

In the arrangement shown in Fig. 3, the two springs 24, 35, at their upper ends are linked to opposite ends of a lever 50 pivoted intermediate its ends, at 51, on a part of frame plate 19. While the tension of each spring may be adjusted, they are so set as, in effect, to balance each other. Thus when the tension of either spring is increased, by movement of the lever 15 or 34 to which it is connected, pivoting motion of lever 50 permits the effect to be transmitted to the

other spring, the tension of which also increases. Thus the degree of braking effect becomes a function of the position of lever 15, decreasing as it rises. But, when it lowers, the braking effect 5 practically disappears on account of motion of lever 34 ahead of motion of lever 15.

Accordingly, with this arrangement, when the switch is in open position and coils 23 are energized, the brake lever 34 moves down ahead of armature lever 15, because the brake lever is very light, as compared with lever 15. Thus, during switch closing, brake pressure is reduced or eliminated, the reason being that during switch closing there is little danger, if any, of arc production.

However, upon switch opening movement, when the coils 23 are deenergized, the brake lever 34 again moves more rapidly than armature lever 15, and in advance of movement of lever 15 wraps 10 the brake band 32 more tightly around the drum 31 and applies a braking effect. This braking effect retards upward motion of lever 15 and thus slows up the increase in resistance through the carbon piles by the reduction of pressure between the members thereof. In this manner, after the contact plate 13 has moved out of contact with terminal members 11, 12, a definite period of time (measured in fractions of a second, of course) elapses before the discharge plate 20 28 moves away from the upper members of the two carbon piles. That period of time is sufficient to enable any high potential which might be generated to be dissipated gradually before the circuit is completely opened. Thus dangerous or destructive arcs are eliminated or prevented.

Fig. 4 illustrates another form of means for retarding movement of the armature lever 15 during switch opening movement. In that view the base again is illustrated at 10 and the armature lever at 15. The brake lever 34, brake band 32 and brake drum 31 of Fig. 3 are entirely omitted, but other parts of the mechanism may be assumed to be the same as illustrated in Fig. 3.

In this arrangement two expanding and contracting bellows 40, 41 are mounted on opposite sides of a plate 42 attached to the base by screws 43, said plate having an opening 44 normally closed by a valve plate 45 seated upwardly against the bottom of the plate by a compression spring 46.

Upon the lever 15 is mounted a metering pin 47 having a tapered end 48 cooperating as a valve with a small opening in the valve plate 45, the upper end of said pin being threaded for vertical adjustment thereof with reference to lever 15.

Fig. 4 illustrates the parts in switch open position. The metering pin is in such position that the large end of its tapered portion nearly closes the small opening in valve plate 45. When the actuating coils 23 are energized, lever 15 is depressed. The space within both bellows is filled with any suitable fluid, either liquid or any suitable gas. When lever 15 is depressed, downward fluid flow carries with it the valve plate 45, thus suddenly and widely opening communication between the upper and lower chambers. Thus, downward motion of lever 15 and closing of the switch contacts is practically unimpeded.

However, when the switch is opened, by deenergizing the coils 23, a retarding effect occurs. Spring 24 urges the armature lever 15 upwardly. Subject to the force of spring 24 and the inherent spring action of the bellows, by which they tend to return to their original condition, fluid

now flows from the lower bellows back to the upper bellows. Spring 46, along with the change in the direction of fluid pressure, causes the valve 45 promptly to seat against the partition plate. Therefore, the oil flowing upwardly can reach the upper chamber only by the small orifice in valve 45, thus retarding the ability of bellows 40 to expand upwardly and permit the lever 15 to rise. Selection of the time of delay is accomplished through proper proportioning between the sizes 10 of ports in the plate 42 and valve 45.

The use of a metering pin with a tapered end portion, permits accurate control of the rate and manner of upward movement of lever 15.

The tapered shank of the pin projects into the orifice in valve plate 45, thereby providing but a small aperture for oil flow. By properly proportioning the taper of the metering pin the rate of upward travel may be controlled. Further, by cutting off the end of the pin at the proper point, the end of the pin ultimately will move entirely out of the orifice and allow for suddenly increased acceleration at any desired point in the range of gradual acceleration.

In both forms of the invention, the switch closes with rapid unimpeded motion of armature lever 15. However, before the circuit is closed magnetically by the engagement of bridge 13 with the terminal plates 11, 12, a shunt circuit is established through a resistance which at first is very high and which is gradually reduced by spring pressure until it can carry substantially full load at the time when the circuit is closed metallically. During switch opening, the circuit is first opened by moving bridge 13 out of contact with terminal plates 11, 12, and then the increase in the resistance of the shunt circuit through the carbon piles is accomplished gradually by relief of spring pressure, and additionally delayed during a period of time sufficient to enable the magnetic field to slowly dissipate its energy without danger to either circuits, apparatus or personnel. The switch as a whole is relatively simple, involves but a few parts not likely to get out of order in service, and is quite compact.

Other advantages of the invention will be apparent to those skilled in the art.

What I claim is:

1. Arc preventing switch mechanism, comprising two pairs of cooperating relatively movable contact members connected in parallel with the members of one pair in one branch and those of the other pair in the other branch of a circuit, the members of one pair being made of relatively low resistance material and those of the other pair including a portion made of variable relatively high resistance material, means for supporting and operating said members in such manner that upon switch opening movement the members of the low resistance pair separate first, means effective upon switch closure for reducing said variable high resistance, and means energized by movement of said switch, and responsive thereto, and effective thereon whereby to retard the rate of change of said variable high resistance during switch opening movement.

2. Switch mechanism of the character described in claim 1, in which said variable relatively high resistance consists of a carbon pile the resistance of which is varied by varying the pressure upon the pile.

3. Arc preventing switch mechanism, comprising two relatively low resistance terminals separated by a gap, and means for closing said gap

by way of two parallel branches of a switch circuit, one branch including a relatively low resistance bridge member adapted to open the gap and contact both terminals, and the second branch including two piles of high resistance plates which respectively at one end engage said terminals, and a relatively low resistance bar adapted to contact the opposite ends of said piles, means for movably supporting said bridge member and low resistance bar to move together toward and from said terminals during switch closing and opening movements, yielding means between said bridge member and resistance bar compelling closure of the second branch before the first during switch closing, and opening of the second branch after the first during switch opening, means for moving said member and bar into and out of switch closing position and for applying and relieving pressure between the high resistance plates during such motion, and means for retarding change of such pressure during switch opening movement during a period of time sufficient to permit gradual dissipation of the transient electrical surge incident to switch opening movement said retarding means being responsive to and energized by the aforesaid means for moving said member and bar.

4. Arc preventing switch mechanism comprising two terminals separated by a gap, a pivoted lever, two sets of current conducting members actuated by said lever and adapted respectively to close and open parallel paths between said terminals, one path including variable high resistance and the other low resistance members, means arranged upon switch closing to reduce the high resistance and upon switch opening to increase the high resistance, and means responsive to movement of said lever, and effective thereon, whereby to retard the rate of increase of said high resistance by retarding switch opening movement of said lever.

5. Arc preventing switch mechanism comprising two pairs of cooperating relatively movable contact members connected in parallel with the members of one pair in one branch and those of the other pair in the other branch of a circuit, the members of one pair being made of relatively low resistance material and those of the other pair including a portion made of variable relatively high resistance material, means for supporting and operating said members in such manner that upon switch opening movement the members of the low resistance pair separate first, means effective upon switch closure for reducing said variable high resistance, and means energized by switch opening movement and responsive thereto, and effective thereon, whereby to retard the rate of increase of said variable high resistance during such switch opening movement.
